Specification for Design.

Patented Nov. 23, 1915.

Application filed May 14, 1915. Serial No. 28,212. Term of patent 14 years.

To all whom it may concern:

Be it known that I, CHARLES W. LA RUE, a citizen of the United States, residing at New York, borough of Brooklyn, in the county of Kings and State of New York, have invented a new and original Design for Cup-Dispensers, of which the following is a specification, reference being had to the accompanying drawing, forming part thereof, wherein—

Figures 1, 2 and 3 are a front elevation, a side elevation and a bottom view respectively of a cup dispenser, showing my new design.

Copies of this patent may be obtained for five cents each, by addressing the "Commissioner of Patents, Washington, D. C."

I claim:

The ornamental design for a cup dispenser as shown.

Signed at New York, in the county of New York and State of New York, this 12th day of May, 1915, before two subscribing witnesses.

CHAS. W. LA RUE.
